[57] CLAIM

The ornamental design for a combined magnetic holder
with arm band, as shown and described.

DESCRIPTION

FIG. 1 is a top plan view of the combined magnetic
holder with arm band showing my new design;

FIG. 2 is a bottom plan view;

FIG. 3 is a side elevational view;

FIG. 4 is an end elevational view thereof;

FIG. 5 is a top perspective view; and

FIG. 6 is a perspective view in a position of use.

FIG. 1

FIG. 2

FIG. 3

FIG. 4

FIG. 5

FIG. 6
